COMBINATION AUTOMOBILE AND BOAT

Cheston L. Eshelman, % The Cheston L. Eshelman Co.,
109 Light St., Baltimore, Md.

Filed July 15, 1960, Ser. No. 61,371

Term of patent 14 years

(Cl. D14—3)

FIG. 1.

FIG. 2.

FIG. 3.

Des. 190,723

PAGE 2

FIG.4.

FIG.5

FIGURE 1 is a side elevational view of a combination automobile and boat, showing this new design.

FIGURE 2 is a top plan view.

FIGURE 3 is a cross-sectional view on line 3-3 of FIGURE 1.

FIGURE 4 is a front elevational view.

FIGURE 5 is a rear elevational view.

FIGURE 6 is a bottom plan view thereof.

FIGURE 7 is a fragmentary sectional view taken on the lines 7-7 of FIGURE 6.

FIGURE 8 is a fragmentary sectional view taken on lines 8-8 of FIGURE 6.

The dominant features of the new design reside in the full line portions of the drawings.

I claim:

The ornamental design for a combination automobile and boat, substantially as shown and described.
